UNITED STATES PATENT OFFICE.

EDWARD CHESHIRE, OF MILWAUKEE, WISCONSIN.

SHEET-REGISTER DEVICE.

964,756.

Specification of Letters Patent. Patented July 19, 1910.

Application filed July 30, 1909. Serial No. 510,478.

To all whom it may concern:

Be it known that I, EDWARD CHESHIRE, a citizen of the United States, residing at Milwaukee, in the county of Milwaukee and 5 State of Wisconsin, have invented new and useful Improvements in Sheet-Register Devices, of which the following is a full, clear, concise, and exact description, reference being had to the accompanying drawing, 10 forming a part of this specification.

My invention pertains to the registering of sheets of paper upon which a printing operation is to be performed, and relates more particularly to automatic registering 15 devices for use in connection with presses of what is known as the Gordon type.

Attempts have been made from time to time to provide an efficient automatic sheet register for platen presses but no device has 20 as yet been produced which has satisfied all the requirements of the case.

It is the object of my invention, therefore, to provide a certain, efficient, and easily manipulated device for registering the 25 sheets of paper to be operated upon in a printing press.

I have embodied my invention in several devices, one of which I have chosen as satisfactorily indicating the various features 30 thereof. This embodiment is illustrated in the accompanying drawings, in which—

Figure 1 is a plan of the platen of a Gordon press showing the gripper fingers raised to permit paper to be fed and showing the register arm as just receiving a 35 sheet of paper; Fig. 2 is a fragmentary view similar to Fig. 1, but showing the gripper fingers partially closed and the sheet moved by the register arm against the end stops, 40 this view also illustrates in dotted lines the position of the parts when the sheet has been moved against the side stop; Fig. 3 is a side elevation showing the parts in the position indicated in full lines in Fig. 2, and; Figs. 45 4, 5, 6, 7 and 8 are detail views of various portions of the registering device.

The device is illustrated as applied to the platen of a press of the Gordon type, the platen being indicated as 10 on the drawings. The platen is provided with the usual 50 tympan-retaining bails 11 and end stops 12 against which the sheets of paper are adapted to be successively placed. A side stop 13 is also provided against which the side of

the sheet engages when the sheet is in proper 55 register. Pivoted to the platen is the ordinary gripper bar 14 which carries the gripper fingers 15, the function of which is to retain the sheet in place during the printing operation and prevent the sheet from adhering to the type when the platen recedes. The above are among the ordinary equipments of a Gordon press.

The object of my invention is effected by providing automatic means for moving the 65 sheet first against one set of stops and then against the other, by which movements the sheet is brought into exact register for printing, and the means for effecting these movements of the sheet which are illustrated in the accompanying drawings are 70 constituted as follows.

A bracket 16 (Fig. 4) having forwardly projecting hooks 17 for engaging beneath the platen is secured to the platen by means 75 of clamping blocks 18 and 19 which are attached to the bracket by means of screws and engage at their ends over the front tympan-retaining bail 11. By loosening the clamping blocks 18 and 19, the register device may be adjusted to any desired lateral position on the platen. A lug 20 extends 80 upwardly and slightly rearwardly from the bracket 16 and serves as a post to which a hook lever 21 is pivoted. The hook lever 85 21 (Fig. 5) surrounds three sides of the gripper bar 14 and has a pair of upwardly and forwardly extending lugs 22 which embrace the lug 20 of the bracket 16 and are pivotally connected thereto. One of the lugs 90 22 is formed near the base thereof with a pivot hole adapted to receive a horizontal pivot pin 23. The horizontal pivot pin 23 is provided with a vertical pivot pin 24 (Fig. 7) and forms a compound joint between the lug 22 and a lost motion lever 25 which is pivoted about the pin 24. The lever 25 carries the register arm, and it will be readily seen that, as the gripper bar 14 closes toward the platen and the gripper 95 fingers are thereby moved toward the platen to grip the sheet, the lower end of the lug 22 and therefore the lost motion lever 25 will be moved away from the platen. It is this movement which effects the registering of the sheet. The lost motion lever 25 has a laterally extending arm 26, the end of which enters an elongated slot 27 with 100

which the clamping block 19 is formed (Fig. 6), and this lever is also formed with an undercut slideway 28 in which the register arm 29 is inserted. The register arm 29 is beveled to conform with the slideway 28 and is of slightly greater width, the slideway being formed with a longitudinal slot 30 which enables the metal of the lever 25 to spring slightly apart to permit the 10 register arm to enter the slideway and be frictionally retained therein. The effect of this is that the register arm is normally supported in the slideway with sufficient firmness to enable it to operate properly, 15 while its operative length may be readily adjusted as desired, to suit the various sizes of paper used. The horizontal pivot pin 23 can turn readily and, as this pin is situated somewhat above the level of the platen, 20 the outer end of the register arm 29 will be held against the tympan by the weight of the parts and will slide closely thereupon during its movements to and fro. The outer end of the register arm is formed with a 25 knife edge in order that it may readily enter beneath the sheets of paper when they are placed upon the platen. Upon the outer end of the register arm is mounted a spring gripping finger 30, the upper end of which 30 is turned up to enable the sheets to enter readily between it and the register arm 29. The inner end of the finger 30 is enlarged and clamped over the register arm as at 33, so as to form a frictional connection between 35 the gripping finger and the register arm in order to enable the outer end of the former to be adjusted to the required distance from that of the latter.

The operation of the device is as follows:

- 40 When a sheet of paper is fed to the platen against the end stops 12 its front edge will enter between the gripping finger 30 and the register arm 29. This is the condition of parts illustrated in Fig. 1, the sheet being 45 shown in full lines as having not been placed in the correct position against the end and side stops, and in dotted lines in its ultimate position. When a sheet is being fed the gripper fingers 15 will of course be in the 50 position shown, that is, open. As the gripper bar 14 closes toward the platen during the movement of the latter into parallelism with the bed of the press, the lost motion lever 25, together with the register arm 29, will be pulled forward over the platen, 55 whereby the sheet will be pulled down against the end stops 12, that is, if it was not originally placed in engagement with these stops. If the sheet was originally placed in 60 engagement with the end stops 12, or after it has been pulled into engagement therewith by the register arm, the latter will merely slip forward over the paper, maintaining the register until the parts reach the 65 condition shown in full lines in Fig. 2, in

which the arm 26 of the lost motion lever has just touched the front end of the slot 27 of the clamping block 19. After the arm 26 strikes the end of the slot 27 the further movement of the gripper bar will effect a 70 rocking of the lost motion lever and register arm toward the right about the vertical pivot 24, the effect being that, if the sheet was not placed in the first instance in its correct position against the side stop 13, it 75 will be moved against this stop by the register arm. If, however, the sheet was originally placed in the correct position, or after the sheet has been moved against the side stop as above described, the arm 29 and gripping 80 finger 30 will merely slide upon the sheet and maintain it in its register. The parts are then in the condition shown in dotted lines in Fig. 2, the sheet being shown as in perfect register. When the printing operation has been performed and the platen begins to return to the feeding position and the grippers 15 consequently begin to open, the register arm will be moved backward over the tympan in its inclined position until 90 the latter part of the movement of the platen, when the arm 26 of the lost motion lever will strike the rear end of the stop 27 whereupon it and the register arm will be rocked back into the position shown in Fig. 1 ready for 95 receiving and registering another sheet. It will thus be seen that the sheets, if not fed correctly in the first instance, are automatically moved into engagement first with the end stops and then against the side stop 100 whereby a perfect register is insured. If the sheets are fed correctly in the first instance their proper register is maintained by the device.

The device is simple and quite certain in 105 its operation, moreover, it may be very readily adjusted to suit the particular requirements of each size and kind of paper used and may be quickly and easily attached to any ordinary press of the Gordon or other 110 similar type.

The automatic registering device according to my invention is exceedingly useful in connection with hand fed presses but its employment is particularly advantageous in 115 connection with presses having automatic feeding devices, such, for instance, as that described in my copending application Serial No. 508,896, filed July 22, 1909.

Having thus described my invention, what 120 I claim as new and desire to secure by Letters Patent, is:

1. The combination with a platen having an end stop and a side stop thereon, of automatic means for moving a sheet of paper 125 from its stationary position upon the platen into engagement first with one of said stops and then with the other.

2. The combination with a platen having an end stop and a side stop thereon, of au- 130

omatic means for moving a sheet of paper into engagement first with the end stop and then with the side stop.

3. The combination with a platen having an end stop and a side stop thereon and having a gripper bar operatively connected therewith, of means actuated by said gripper bar for moving a sheet of paper into engagement first with the end stop and then 10 with the side stop.

4. The combination with a platen having two laterally separated end stops, of a register arm located between said end stops, a non-positive sheet-grasping device carried 15 by said register arm, and automatic means for moving said register arm forward upon the platen whereby the sheet of paper is brought against said end stops and left in engagement therewith.

20 5. The combination with a platen having two laterally separated end stops thereon and a gripper bar operatively connected with said platen, of a register arm located between said stops for operating upon a sheet 25 of paper, and connecting means between said register arm and the gripper bar whereby the register arm is moved forward upon the platen to bring the sheet into engagement with said end stops.

30 6. The combination with a platen having an end stop and a side stop thereon, of a device arranged to lie upon said platen and having means for operating upon a sheet of paper, automatic means for effecting a longitudinal pull upon said device, and means 35 for engaging said device whereby the latter is caused to move laterally upon the platen to bring the sheet of paper into engagement with the side stop.

40 7. The combination with a platen having an end stop and a side stop thereon and a gripper bar operatively connected with said platen, of a device arranged to lie upon said platen and having means for operating upon 45 a sheet of paper, connection means between said device and said gripper bar whereby a longitudinal pull is effected upon said device, and means carried by said platen for engaging said device whereby the latter is 50 caused to move laterally upon said platen to bring the sheet into engagement with the side stop.

55 8. The combination with a platen having an end stop and a side stop thereon and a gripper bar operatively connected with said platen, of a register arm for operating upon a sheet of paper, and connecting means between said register arm and the gripper bar for effecting first a longitudinal and then a 60 lateral movement of said register arm upon the platen to bring the sheet into engagement first with the end stop and then with the side stop.

65 9. The combination with a platen having an end stop and a side stop thereon, of a lost

motion lever, a register arm carried by said lever for operating upon a sheet of paper, means for moving said lever longitudinally upon the platen, and means for changing said longitudinal movement to a lateral movement whereby said register arm is caused to bring the sheet of paper first against the end stop and then against the side stop. 70

10. The combination with a platen having an end stop and a side stop thereon, of a lost motion lever, a register arm carried by said lost motion lever for operating upon a sheet of paper, means for moving said lever longitudinally upon the platen, and a stop for engaging said lever during its longitudinal 75 movement and causing it to move laterally, whereby said register arm is caused to bring the sheet of paper first against the end stop and then against the side stop.

11. The combination with a platen having an end stop and a side stop thereon and a gripper bar operatively connected with said platen, of a lost motion lever, a register arm carried by said lever for operating upon a sheet of paper, connection means between 85 said lever and the gripper bar whereby said lever is moved longitudinally upon the platen, and a stop for engaging said lost motion lever during its longitudinal movement and causing it to move laterally whereby said 90 register arm is caused to bring the sheet of paper first against the end stop and then against the side stop.

12. The combination with a platen having an end stop and a side stop thereon, of a lost motion lever having means for operating upon a sheet of paper, and means for moving said lever first toward one of said stops and then toward the other stop, whereby the sheet of paper is moved first against one stop 100 and then against the other. 105

13. The combination with a platen having an end stop and a side stop thereon, of a register arm for operating upon a sheet of paper, a lost motion lever connected with 110 said register arm in such manner that the latter may be longitudinally adjusted relatively to the lever, and means for effecting first a longitudinal and then a lateral movement of said lost motion lever, whereby the sheet is brought first against the end stop and then against the side stop. 115

14. The combination with a platen having an end stop and a side stop thereon, of a register arm provided with a gripping member for receiving a sheet of paper, a lost motion lever carrying said register arm, and means for effecting first a longitudinal and then a lateral movement of said lost motion lever, whereby the sheet is brought first 120 against the end stop and then against the side stop. 125

15. The combination with a platen having an end stop and a side stop thereon, of a register arm provided with an adjustable 130

- gripping member for receiving a sheet of paper, a lost motion lever carrying said register arm, and means for effecting first a longitudinal and then a lateral movement of 5 said lost motion lever, whereby the sheet is brought first against the end stop and then against the side stop.
16. The combination with a platen having an end stop and a side stop thereon and 10 a gripper bar operatively connected with said platen, of a bracket carried by said platen adjacent said gripper bar and having an upwardly extending lug, a lever pivoted to the lug of said bracket and engaging said 15 gripper bar, stops carried by said bracket, a lost motion lever pivoted to said first-named lever and having a portion thereof extending between said stops, and a register arm carried by said lost motion lever 20 and operating upon a sheet of paper to bring the same into engagement, first with the end stop and then with the side stop of the platen.
17. A sheet registering device for use in 25 connection with Gordon and similar presses, comprising a device arranged to lie upon the platen, said device having means for operating upon a sheet of paper, mechanism, arranged to be connected to a moving part of 30 the press, for effecting a longitudinal movement of said device, and means carried by the press for changing said longitudinal movement into a lateral movement.
18. A sheet registering device for use in 35 connection with Gordon and similar presses, comprising a member arranged to be operatively connected with the gripper bar, a device connected to said member and arranged to lie upon the platen, said device 40 having means for operating upon a sheet of paper, and a member arranged to be attached to the platen said member comprising means for changing the longitudinal
- movement of said device, effected by the rocking of the gripper bar, into lateral 45 movement.
19. A sheet registering device for use in connection with Gordon and similar presses comprising a member arranged to be attached to the platen, a second member arranged to be operatively connected with the gripper bar, connection means between said members, a lever arranged to lie upon the platen, said lever having means for operating upon a sheet of paper and being connected with said second-named member, and means carried by said first-named member for engaging said lever whereby the rocking movement of said gripper bar is caused to effect a lateral movement of said lever. 50 55 60
20. A sheet registering device for use in connection with Gordon and similar presses comprising a member adapted to be connected to the gripper bar of the platen, a second member pivoted to said first mentioned member and adapted to be attached to the platen adjacent the gripper bar, and an arm pivoted to said first mentioned member and arranged to lie upon the platen, said arm having at its end means for engaging a 65 70 sheet of paper.
21. The combination with a platen having an end stop and a side stop thereon, of a member carrying a sheet-grasping device arranged to receive a sheet of paper, and 75 means for imparting a compound movement to said member whereby the sheet is brought into engagement, first with one of said stops and then with the other.

In witness whereof, I have hereunto subscribed my name in the presence of two witnesses.

EDWARD CHESHIRE.
